UNITED STATES PATENT OFFICE.

EMERSON P. JENNINGS, JR., OF LEHIGHTON, PENNSYLVANIA.

PRINTING-PRESS.

1,173,579.

Specification of Letters Patent. Patented Feb. 29, 1916.

Application filed January 26, 1914. Serial No. 814,299.

To all whom it may concern:

Be it known that I, EMERSON P. JENNINGS, Jr., a citizen of the United States, residing at Lehighton, in the county of Carbon and State of Pennsylvania, have invented certain new and useful Improvements in Printing-Presses, of which the following is a specification, reference being had therein to the accompanying drawing.

10 This invention relates to printing presses and more particularly to an adjusting device for a press in which one member of the printing couple has reciprocatory movement.

15 The object of the invention is to provide means for adjusting the movement of the movable member of the couple, to regulate the impression, by adjusting the throw of the actuating device for said movable

20 member.

In the accompanying drawings, Figure 1 is a side elevation of a printing press embodying the invention; and Fig. 2 is a detail view of the adjusting device.

25 As shown in these drawings the invention is applied to a Cartwright press, as shown and described in Patent No. 926,851, of July 26th, 1909. It is unnecessary to describe this press in detail but it is sufficient to say 30 that it comprises a main frame 1 having mounted therein a normally stationary platen 2 and is provided with a combined form-bed 3 and inking drum 4 which are carried by slide blocks 5 mounted in guide-

35 ways 6 formed in the side members of the main frame 1. The ink distributing rollers, which are shown at 7, are mounted on brackets 8 which, in turn, are journaled on the axis of the combined form-bed and ink

40 drum and move with said form-bed and ink drum. Independent rotatory movement is imparted to the brackets 8 to carry the distributing rollers about the drum and over the form-bed by means of a sprocket wheel

45 9 which is connected by a sprocket chain 10 with a second sprocket wheel 11 on a main drive shaft 12, this last-mentioned sprocket wheel being mounted eccentrically on the shaft to maintain a proper tension on the

50 chain during the reciprocatory movement of the form-bed and inking drum. Reciprocatory movement is imparted to the form-bed and inking drum by means of pitmen 13 secured to the respective slide blocks and 55 connected with the driving shaft 12, this connection being preferably made through

gears 14 which also serve to drive the shaft. Each gear is provided with a wrist pin 15 which is journaled in a bearing block 16 carried by the respective pitmen 13. In 60 order to adjust the throw of the form-bed and thus regulate the impression I adjust the position of the pitmen relatively to the wrist pins 15. This adjustment also has another function, that of regulating the 65 tension on the driving chains for the distributing rollers.

The adjustment of the pitmen relatively to their wrist pins may be secured in any suitable manner. In the present instance 70 I have adopted a very simple method which consists in mounting the bearing block 16 of each pitman in a guideway 17 of a length considerably greater than the length of the bearing block and filling the spaces between 75 the ends of the bearing block and the respective ends of the guideway with a plurality of plates or fillers 18. A set screw 19 is mounted in the pitmen and bears against the plates at one end to clamp the whole 80 structure firmly in position. By loosening the set screw 19 and shifting one or more of the fillers 18 from one side of the bearing block to the other the position of this bearing block and consequently the position of 85 the wrist pin relatively to the pitman is altered and the throw of the pitman and the form-bed connected therewith is adjusted. I find that this method of adjusting 90 the impression is a very simple and decidedly effective one. The plates are made of material of such thinness that very fine adjustments can be made and these can be made without taking down any of the machinery or altering any other adjustments. 95

While I have shown and described one embodiment of the invention it will be understood that this has been chosen for the purpose of illustration only and that I do not desire to be limited to the details of construction shown and described, for obvious modifications will occur to a person skilled in the art.

Having thus fully described my invention, what I claim as new and desire to secure by Letters Patent, is:—

In a printing press, the combination, with a shaft, means for rotating said shaft, a sprocket wheel eccentrically mounted on said shaft, a form-bed movable toward and away from said shaft, a roller carriage mounted for rotation about said form-bed,

a sprocket wheel connected with said roller carriage, a sprocket chain connecting the sprocket wheel on said roller carriage with the sprocket wheel on said shaft, and a 5 crank wheel mounted on said shaft and having a wrist pin, of a pitman connecting said crank wheel with said form-bed and provided at that end adjacent to said crank wheel with an elongated guideway, a bearing block mounted in said guideway to receive said wrist pin, and interchangeable plates interposed between the ends of said bearing block and the respective ends of said guideway, whereby the shifting of one

or more of said plates from one end of said bearing block to the other end thereof will alter the distance between the axes of said sprocket wheels and tighten or loosen said sprocket chain, and means for securing said plates and said bearing block in their adjusted positions.

In testimony whereof, I affix my signature in presence of two witnesses.

EMERSON P. JENNINGS, JR.
